CLAIM

The ornamental design for an autonomous manned aircraft as shown and described.

DESCRIPTION

1. Autonomous manned aircraft
FIG. 1.1 is a front view for an autonomous manned aircraft showing my new design;
FIG. 1.2 is a rear view thereof;
FIG. 1.3 is a left-side view thereof;
FIG. 1.4 is a right-side view thereof;
FIG. 1.5 is a top plan view thereof;
FIG. 1.6 is a bottom plan view thereof;
FIG. 1.7 is a front, left-side, and top perspective view thereof;
FIG. 1.8 is a rear, right-side, and top perspective view thereof;
FIG. 1.9 is a partial enlarged view of the indicated area "1.9" in FIG. 1.1;
FIG. 1.10 is a partial enlarged view of the indicated area "1.10" in FIG. 1.1;
FIG. 1.11 is a partial enlarged view of the indicated area "1.11" in FIG. 1.6;
FIG. 1.12 is a partial enlarged view of the indicated area "1.12" in FIG. 1.6; and
FIG. 1.13 is a partial enlarged view of the indicated area "1.13" in FIG. 1.6.
The broken lines seen in FIGS. 1.1, 1.6 and 1.9 to 1.13 depict the boundaries of the enlargements and form no part of the claimed design.
